BLOWTORCH ATTACHMENT FOR LADLE TABLES

Martin I. Szulerecki, Sauk Rapids, Minn.

Application November 6, 1946, Serial No. 708,167

1 Claim. (Cl. 126—240)

1

My present invention relates to a ladle-support for a blow-torch adapted especially for use as an attachment to liquid fuel burners or heaters of the hand-torch or portable blow-torch type. The attachment of my invention is capable of installation on standard types of blow-torches that include a holder for a soldering-iron, and in equipping a blow-torch with my ladle-support or table, the soldering iron is removed, and the ladle is substituted and held by the means for attaching the table or support to the blow-torch.

By the utilization of my attachment, the ladle is supported on the blow-torch in position for heating and melting the selected metal, and the portable torch with its attachment may with facility be employed for pouring the molten metal from the supported ladle.

The primary object of the invention is the provision of an attachment or appliance of this type that consists of a minimum number of parts that may with facility be manufactured at low cost of production, and which parts may with convenience be assembled, adjusted, and installed for use with a blow-torch or similar appliance, without necessity for skilled labor, and with accuracy and convenience.

The invention consists in certain novel combinations and arrangements of parts, and in the means for attaching these combined parts to a blow-torch or the like, as will hereinafter be described, and more specifically set forth in my appended claims.

In the accompanying drawings I have illustrated one complete example of the physical embodiment of my invention in connection with a blow-torch, wherein the parts are combined and arranged in accord with one mode I have devised for the practical application of the principles of my invention. It will, however, be understood that changes and alterations are contemplated and may be made in these exemplifying drawings, mechanical structures, and installation, within the scope of my claims without departing from the principles of the invention.

Figure 1 is a view in side elevation showing in dotted lines a portion of a standard type of blow-torch, equipped with the attachment of my invention, and also showing in dotted lines a ladle supported in position for heating, and for pouring the molten metal.

Figure 2 is a top plan view of the attachment of my invention; and

2

Figure 3 is an end elevation of the attachment as seen from the right in Fig. 1.

In order that the general arrangement and utility of parts may readily be understood, I have shown by dotted lines in Fig. 1 a portion of a standard type of portable gasoline blow-torch including the fuel tank forming a base B, the upright fuel supply pipe F rising from the tank, and the horizontally disposed torch T upon which the usual holder H is mounted to hold a conventional soldering iron. In equipping the blow torch with the attachment of my invention the soldering iron is removed, and therefore not illustrated in the drawings; and a ladle having a pouring pot or bowl L and handle A is substituted for the soldering iron.

The handle A of the ladle is held or retained by the holder H which is threaded into a socket of a boss C which is rigid with the top face of the torch, and this holder for the ladle is also utilized as means for attaching the ladle support over and parallel with the torch T.

By means of my attachment the bowl L is supported directly in front of the torch to receive the blast for heating the metal within the bowl, and the portable blow-torch is manipulated by hand for pouring the molten metal from the bowl.

The appliance of my invention includes a circular open-center, preferably sheet-metal, supporting plate or ring-shaped table 1, having an interior edge-notch 2 to accommodate the pouring spout S of the ladle L, and a radially extending, integral, attaching blade or arm 3 having a longitudinally extending slot 4.

This open-center supporting plate or ring-shaped table is mounted above the torch T, and secured thereto by means of the holder H which is threaded through the slot 4 of the arm 3 and firmly fixed on the socket-boss C of the torch. As shown, the bowl of the ladle fits neatly into the open center table and the handle A of the ladle is retained by the holder H; and the slotted attaching arm 3 may be utilized in adjusting the bowl with relation to the torch for effective heating of the contents of the bowl of the ladle.

For bracing the outwardly projecting table, a sectional longitudinally adjustable, and obliquely disposed brace is provided, which includes a leg or sheet metal plate 5 having an angular foot 6 that is fashioned at its outer edge with a notch 7 for engagement with the fuel feed pipe F of the blow-torch; and this metal plate is fashioned with a longitudinally extending slot 8 for co-action with a complementary

plate 9 forming an arm of the adjustable brace.

The slidably adjustable leg 5 and arm 9 are fixed in adjusted position by means of a headed screw bolt 10 passed through a hole in the arm and through the slot 8 of the leg 5, and a clamp nut 11, preferably of the wing type, is utilized for locking the arm and the leg in adjusted position.

As best seen in Fig. 1, the arm 9 of the brace is fashioned with a bent or hook-shaped head 12, and a screw bolt 13 is passed through registering holes in the head and the table 1 for rigidly fastening the adjusted brace to the ladle table.

The attachment may be applied to the blow-torch for use by a right-hand craftsman, or by a left-hand craftsman, by first removing the brace from the table and then by turning over and reversing the relative position of the table, so that the notch 2 for the spout S will be at the opposite side of the center line in Fig. 3. In this reversed position the brace may again be attached to the table, and the table and brace affixed to the blow-torch for use therewith in supporting the ladle.

By means of the slotted attaching arm 3 of the table and the adjustable brace or bracket 5-9, it will be apparent that the device may be fitted with facility to a blow-torch or the like to locate the ladle in desired position for effectively heating the contained metal, and the whole structure may skilfully be manipulated for pouring the molten metal.

Having thus fully described my invention, what I claim as new and desire to secure by Letters Patent is:

In an attachment for supporting a ladle in heating position over a portable blow-torch, the combination with an open-center ring shaped

table adapted to receive the bowl of the ladle, of a slotted arm rigid with the table, a holder for the handle of the ladle coacting with said slotted arm for attaching said arm to the blow-torch, an angularly disposed bracing arm with a hook-shaped head bolted to said table, said bolt passing through said hook-shaped head, a slotted adjustable leg secured to said angularly disposed bracing arm, and securing means for securing 10 said slotted adjustable leg to said angularly disposed bracing arm, said means including a threaded bolt and a wing nut, said slotted adjustable leg being provided at its other end with an angular foot having a notch for engagement with said torch.
